UNITED STATES PATENT OFFICE

FRANK W. MARSH, OF DANVERS, MASSACHUSETTS

CONTAINER FOR USE IN PACKING AND HANDLING MERCHANTISE

Application filed September 17, 1928. Serial No. 306,468.

My invention has for its object to provide a combination of unit cartons, that is to say, cartons that contain a unit of merchandise, and a large carton, all of the cartons being 5 so constructed and assembled together that the contents of the unit cartons may be displayed for advertising and shown to customers without being removed therefrom and the size and shape and all individual characteristics of the articles may be observed 10 without effort. My device also assures safety against breakage of the contents, minimizes expense in packing; and provides a combination of economy, safety, store decoration, 15 window display value, general sales appeal and the delivery of properly made contents. Also visual inspection of contents and complete tests of the same, electrical and otherwise, may be made without removing contents 20 from the individual carton.

In the drawings that accompany and are made a part of this specification, Figure 1 is a perspective view of my combination set up so as to display the contents thereof; Figure 25 2 is a perspective view of a unit carton and contents; Figure 3 is a side view of a unit carton and contents; Figure 4 is a rear view of the bottom of the large carton, showing apertures therein, all other parts being omitted; and Figure 5 is a detail of a pattern 30 of a unit carton showing positions of the apertures therein. Figure 6 is a front view of bottom of the container with back, the back walls of the individual cartons resting thereon, all other parts being omitted; Figure 7 35 is a rear perspective view of container with individual cartons positioned therein, the whole being set up for display purposes.

I provide a plurality of unit cartons 1. 40 Each unit carton is provided with lateral apertures 2, that is to say, in each of the four sides of a unit carton are openings as shown in Figures 2 and 3. The openings in each carton are preferably cut or stamped out 45 before the carton is made up in its final form for use, (see Figure 5); and they are so cut that when the carton is made up, one-half of each opening will be in a side of the carton; the result being that there will 50 be two openings in each side when the carton

has been made to assume its final shape, (see Figure 3). The shape and size of the apertures may be varied as desired. My illustrations show a form of aperture with straight parallel edges, but I do not mean 55 to limit myself to this shape. The cartons and apertures being of uniform size and shape, it will be found that when two or more cartons are placed side by side as shown in Figure 1, the apertures in a side of each 60 carton in the row will form continuous apertures with those in the adjacent cartons, and that these apertures are of the same size and shape as the apertures cut in each carton before assembling. This is true of all sides 65 of the cartons, so that the sides are interchangeable when the unit cartons are assembled in the large carton.

I provide a large carton 3 of sufficient size to hold a plurality of the unit cartons 1. 70 In the bottom of the large carton 3 I provide apertures 5, similar to the apertures in the unit cartons, but so cut that when the unit cartons are assembled in the large carton the apertures 5 in the large carton 75 will be positioned in a direction opposite to the apertures 2 in the front walls of the unit cartons but lying in the same direction as the openings in the rear walls of the unit cartons as shown in Figures 6 and 7. Upon 80 assembling the unit cartons in the large carton the effect is that of lattice work enclosing the articles contained in the unit cartons. The articles may be seen clearly 85 through the apertures. For display purposes, a light placed as indicated in Figure 7 will shine through the apertures in the container unobstructed by the apertures in the rear walls of the unit cartons. Daylight 90 will pass through in the same manner. Also the unit cartons may be handled individually and the articles therein may be examined from all sides without being removed therefrom. 95

The large carton 3 may be of any well known form, with turn-back cover 6 and may be provided with supports 7 at the back for setting up in display position and when the unit cartons are assembled therein the whole 100

makes a unique and attractive appearance.
Claims:

Claims:

1. In a device of the class described, the combination of a container having apertures in the bottom thereof and a plurality of cartons in the container, apertures in the walls of the cartons, the apertures in the rear walls of the cartons adjacent to the bottom of the container being superposed in parallel positions upon the apertures in the container.

cartons and container in alignment and the apertures in the front walls of the cartons being transverse to the apertures in the bottom of the container and the apertures in the rear walls of the cartons.

FRANK W. MARSH. 70

15 2. In a device of the class described, the combination of a container having apertures in the bottom thereof and a plurality of cartons in the container, apertures in the walls of the cartons, the apertures in the rear walls of the cartons adjacent to the bottom of the container being superposed in parallel positions upon the apertures in the container and the apertures in the front walls of the cartons 20 being transverse to the apertures in the bottom of the container.

76

3. In a device of the class described, the combination of a container having apertures in the bottom thereof and a plurality of cartons in the container, apertures in the walls of the cartons, the apertures in the rear walls of the cartons adjacent to the bottom of the container being superposed in parallel positions upon the apertures in the container and the apertures in the front walls of the cartons being transverse to the apertures in the bottom of the container and the apertures in the rear walls of the cartons.

80

35 4. In a device of the class described, the combination of a container having apertures in the bottom thereof and a plurality of cartons in the container, apertures in the walls of the cartons, the apertures in the rear walls of the cartons adjacent to the bottom of the 40 container being superposed upon the apertures in the bottom of the container with the edges of the apertures in the rear walls of the cartons and container in alignment.

100

5. In a device of the class described, the
45 combination of a container having apertures
in the bottom thereof and a plurality of car-
tions in the container, apertures in the walls
of the cartons, the apertures in the rear walls
50 of the cartons adjacent to the bottom of the
container being superposed upon the aper-
tures in the bottom of the container with the
edges of the apertures in the rear walls of
the cartons and container in alignment and
55 the apertures in the front walls of the cartons
being transverse to the apertures in the bot-
tom of the container.

110

60 6. In a device of the class described, the combination of a container having apparatus in the bottom thereof and a plurality of cartons in the container, apertures in the walls of the cartons, the apertures in the rear walls of the cartons adjacent to the bottom of the container being superposed upon the apertures in the bottom of the container with the edges of the apertures in the rear walls of the
